(57) **CLAIM**

The ornamental design for a bicycle parking rack, as shown and described.

DESCRIPTION

FIG. 1 is a front perspective view of a bicycle parking rack showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is an enlarged perspective view of the encircled portion in FIG. 1.

The broken lines in the drawing depict portions of the bicycle parking rack that form no part of the claimed design. The dot-dash lines define the bounds of the enlarged portion of FIG. 1 and form no part of the claim.

1 Claim, 8 Drawing Sheets
